UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

SHEET-DELIVERY MECHANISM FOR PRINTING-MACHINES.

1,078,238.

Specification of Letters Patent.

Patented Nov. 11, 1913.

Application filed March 16, 1911. Serial No. 614,794.

To all whom it may concern:

Be it known that I, HOWARD M. BARBER, a citizen of the United States, and resident of Stonington, in the county of New London and State of Connecticut, have invented a new and useful Improvement in Sheet-Delivery Mechanism for Printing-Machines, of which the following is a specification.

The object of this invention is to provide manually controlled means for causing a sheet to be delivered at a predetermined point different from the regular delivery point, for the purposes of inspection.

In all classes of printing and especially in color printing, it is essential that the pressman be able to frequently inspect the product of the press. In ordinary practice the pressman has to manually withdraw the product as it is being automatically delivered, which operation is difficult where the sheet is a large and heavy one.

The object of this invention is to eliminate this difficult manual withdrawal of the sheet for inspection, means under the control of the pressman being employed for causing a sheet to be thrown out on to an inspection table at any time during the operation of the machine.

A practical embodiment of the invention is represented in the accompanying drawings, in which,

Figure 1 represents the delivery mechanism for a web printing machine, in side elevation, the parts being shown in the position which they assume when a sheet is being delivered on to the inspection table. Fig. 2 is a longitudinal vertical section through the same. Fig. 3 is a detail view showing the geared connection between the several operative parts. Fig. 4 is a detail view showing the means for controlling the opening and closing of the grippers on the transfer and delivery cylinders. Fig. 5 is a detail side view showing the position which the parts assume when the product is being regularly delivered on to the sheet receiving table. Fig. 6 is an enlarged detail front view of the manually controlled means for causing the delivery cylinder to deliver a

sheet on to the inspection table. Fig. 7 is a section taken in the plane of the line A—A of Fig. 6. Fig. 8 is a detail view on the same scale as Fig. 6, of the lower end of the control lever for the inspection delivery mechanism, the manually operated latch being shown in its inoperative position. Fig. 9 is a section taken in the plane of the line B—B of Fig. 8, and Fig. 10 is a section similar to Fig. 9, with the manually operated latch shown in its operative position.

The rotary cutters for severing the sheets from the web are denoted by 1, 1*. The transfer cylinder for receiving the sheets from the cutters and transferring them to the delivery cylinder, is denoted by 2. The delivery cylinder is denoted by 3 and the sheet receiving table is denoted by 4. In the present instance the rotary cutters 1, 1*, are provided with three sets of co-acting blades 5, the transfer cylinder is shown as provided with two sets of grippers 6 and the delivery cylinder 3 is shown as provided with four sets of grippers 7. The sheet inspection table is denoted by 8 and is herein shown as located in position to receive the sheets from the delivery cylinder after they have been transferred thereto by the transfer cylinder 2 and before the point of delivery to the sheet receiving table 4. It is to be understood however, that this sheet inspection table 8 may be located at any convenient position around the delivery cylinder 3 and need not be at the position indicated therein.

The strippers for stripping the sheets from the delivery cylinder and guiding them to the forwarding rolls 9, 10, are denoted by 11, and are arranged to be moved into and out of operative position by mechanism to be hereinafter described.

The rolls for feeding the web to the rotary cutters are denoted by 12, 13. The rotary cutters are driven together by their intermeshing gears 14, 15. The geared driving connection between the several parts is as follows: A gear 16 on the shaft of the roll 12 meshes with a gear 17 on the stud shaft 18, which gear 17 meshes with a gear

19 on the shaft of the cutter 1. This gear 19 meshes with a gear 20 on the stud shaft 21, which gear 20 meshes with a gear 22 on the shaft of the delivery cylinder 3. A second gear 23 on the shaft of the delivery cylinder 3, meshes with a gear 24 on the shaft 25 of the transfer cylinder 2, and also with an intermediate gear 26, which in turn meshes with the gear 27 on the shaft of the inspection table forwarding roll 9. This gear 27 meshes with a gear 26* on the other inspection table forwarding roll 10. The shaft 25 of the transfer cylinder 2 is provided with a rotary cam 28 for controlling the movements of the joggers 29, 30, for the sheets on the sheet receiving table 4, through suitable mechanism which need not be specifically described herein as it forms no part of the present invention.

20 A stationary cam 31 is arranged in position to engage the stud roller 32 of the gripper opening lever 33 of each set of grippers 6 on the transfer cylinder 2, for opening each set of grippers to receive a sheet from the rotary cutters 1, 1*, and to open the grippers to transfer the sheet to the grippers 7 on the delivery cylinder 3. The usual spring 34 is provided for closing the grippers 6, when released from the cam 31. 25 A stationary cam 35 is arranged in position to engage the stud roller 36 on the gripper opening lever 37 of each set of grippers 7, for opening the grippers to receive a sheet from the grippers 6 of the transfer cylinder 2. This cam 35 is also arranged to open each set of grippers 7 in position to deliver the sheets on to the sheet receiving table 4. In the present instance the cam 35 is so shaped that the set of grippers is opened 30 for delivering a sheet on to the sheet receiving table 4 and remains open until a sheet is transferred thereto from the grippers 6 of the transfer cylinder 2. The usual spring 38 serves to close the grippers 7 when disengaged from the cam 35.

45 I will now proceed to describe the manually controlled mechanism for opening the grippers 7 and stripping the sheets from the delivery cylinder and delivering them on to the inspection table 8.

50 A cam 39 is fixed to the shaft of the delivery cylinder 3, which cam is provided with a cylindrical rim 40 for nearly its entire circumference, said cylindrical rim being discontinued at one end and at its other end having an inwardly inclined narrow portion 41. A normally closed switch 42 is provided with a curved rim 43 which completes the break in the cylindrical rim 40 of the cam 39 when the switch is closed. 55 A spring 44 serves to normally hold this switch in its closed position. A control lever is fixed to a rock shaft 45, the depending arm 46 of which lever carries a later-

ally movable cam roller 47. A spring 48 65 serves to normally hold the roller 47 in its operative position at the limit of its movement away from the lever arm 46. A manually operated latch 49 hinged at 50 to the lever arm 46, has its free end arranged 70 to be brought into engagement with a disk 51 on the rod 52 which carries the cam roller 47 for holding the cam roller out of its operative position with respect to the cam 39 when so desired. The cam roller 47 is 75 thrown by its spring 48 into its operative position with respect to the cam 39, by releasing the latch 49 from its engagement with the disk 51. An uprising arm 53 of the control lever is fixed to the shaft 45 and 80 a spring 54 serves to normally press the arm 53 forward and thereby the arm 46 with its cam roller 47 rearward. A cam 55 is fixed to the rock shaft 45, so that as the shaft is rocked out of its normal position, the cam 85 will be thrown into position to engage the stud roller 36 on the lever 37 of each set of grippers 7 as the grippers approach the position for delivering the sheets on to the inspection table. The strippers 11 are brought 90 into their operative position for stripping the sheets from the delivery cylinder 3 as the rock shaft 45 is rocked out of its normal position, through an arm 56 and a link 57 connecting the said arm with the arm 53 of 95 the control lever. When the cam roller 47 is held by the manually operated latch 49 out of its operative position, the said roller will be swung to a point within the periphery of the rim 40 of the cam 39. When the 100 control lever is in this position, the cam 55 and the strippers 11 are swung out of their operative position, thus permitting the delivery cylinder 3 to regularly receive the sheets from the transfer cylinder 2 and deliver them on to the sheet receiving table 4. When the pressman desires to inspect the product, he throws the latch 49 out of its 105 operative position, thus permitting the cam roller 47 to be thrown into its operative position. As the delivery cylinder 3 continues 110 its rotation, the roller 47 will travel around within the cylindrical portion of the rim 40, until it reaches the inclined portion 41 within the curved portion 43 of the switch 42. 115 The further rotary movement of the delivery cylinder 3 will cause the roller 47 to ride up the inclined portion 41, as shown clearly in Figs. 6 and 7, on to the cylindrical portion 40 of said cam. The switch 42 120 will be closed immediately by its spring 44, thus providing a continuous cylindrical track for the roller 47. The outward movement of this roller 47 will swing the control lever, thereby rocking the shaft 45 125 away from its normal position against the tension of the spring 54 and will swing the cam 55 and strippers 11 into their operative

position. This will cause the grippers 7 to open in time to permit the strippers 11 to strip the sheets from the cylinder 3 and the rollers 9, 10, will positively feed the 5 sheets on to the inspection table 8, where they may be inspected at leisure by the pressman. As soon as it is desired to stop the delivery of sheets for inspection, the roller 47 is moved laterally out of its operative position by the pressman gripping the handle 51. The roller 47 is held in this 10 position by dropping the latch 49 into engagement with the disk 51. The cylindrical rim 40 on the cam 39 will travel around beneath the roller until the narrowed portion at the switch 42 permits the roller and thereby the lever, to move into their normal position.

A sheet guide 58 is located in position to 20 coat with the strippers 11 to feed the sheets to the forwarding rolls 9, 10.

This mechanism may not only be used for delivering sheets to be inspected, but it may also be used for the purpose of throwing 25 out the first few sheets printed after the press has been standing, as these sheets are not allowed to go in with the regular product.

It is to be understood that by the term 30 "cylinder" I intend to cover any operative device for carrying the sheets through the prescribed paths, and by the term "table" I intend to cover any suitable surface adapted to receive the sheets.

35 It is evident that various changes might be resorted to in the construction, form and arrangement of the various parts without departing from the spirit and scope of my invention; hence I do not wish to limit 40 myself strictly to the structure herein set forth, but

What I claim is:

1. A sheet delivery mechanism including 45 a rotary cylinder arranged to automatically receive the sheets at one point, a sheet receiving table, means for causing the cylinder to regularly deliver the sheets thereto, an inspection table and means for causing the cylinder to deliver sheets thereto, when 50 so desired.

2. A sheet delivery mechanism including 55 a rotary cylinder arranged to automatically receive the sheets at one point, a sheet receiving table, means for causing the cylinder to regularly deliver the sheets thereto, an inspection table and manually controlled means for causing the cylinder to deliver sheets thereto, when so desired.

3. A sheet delivery mechanism including 60 a rotary cylinder arranged to automatically receive the sheets at one point, a sheet receiving table, means for causing the cylinder to regularly deliver the sheets thereto, a sheet inspection table located intermediate

the regular sheet receiving and delivery 65 points of the cylinder and means for causing the cylinder to deliver sheets on to said inspection table, when so desired.

4. A sheet delivery mechanism including 70 a rotary cylinder arranged to automatically receive the sheets at one point, a sheet receiving table and means for causing the cylinder to regularly deliver the sheets thereto, an inspection table located intermediate the receiving and delivery points of said cylinder 75 and manually controlled means for causing the cylinder to deliver sheets on to the inspection table, when so desired.

5. A sheet delivery mechanism including 80 a rotary cylinder, its grippers, means for opening the grippers at predetermined receiving and delivery points, and independent means for opening the grippers at another predetermined delivery point including a gripper operating cam and a manually 85 controlled lever for moving the cam into its operative position.

6. A sheet delivery mechanism including 90 a rotary cylinder, its grippers, means for opening the grippers at predetermined receiving and delivery points and independent means for opening the grippers at another predetermined delivery point including a gripper operating cam, sheet strippers and a manually controlled lever for moving 95 the cam and the strippers into their operative positions.

7. A sheet delivery mechanism including 100 a rotary cylinder, its grippers, means for opening the grippers at predetermined receiving and delivery points and independent means for opening the grippers at another predetermined delivery point including a gripper operating cam, sheet strippers and a manually controlled lever for moving 105 the cam and the strippers into their operative positions, an inspection table and forwarding rolls for feeding the sheets from the strippers on to the inspection table.

8. A sheet delivery mechanism including 110 a rotary cylinder, its grippers, means for opening the grippers at predetermined receiving and delivery points and independent means for opening the grippers at another predetermined delivery point comprising 115 a lever, a gripper opening cam controlled thereby, a cam fixed to rotate with the cylinder, a cam roller carried by the lever and means for moving the cam roller into and out of its engagement with the last 120 named cam.

9. A sheet delivery mechanism including 125 a rotary cylinder, its grippers, means for opening the grippers at predetermined receiving and delivery points and independent means for opening the grippers at another predetermined delivery point comprising a lever, a gripper opening cam con-

trolled thereby, a cam fixed to rotate with the cylinder, a cam roller carried by the lever, means for moving the cam roller into and out of its engagement with the last 5 named cam and sheet strippers moved into and out of their operative position by said lever.

In testimony, that I claim the foregoing

as my invention, I have signed my name in presence of two witnesses, this thirteenth 10 day of March A. D. 1911.

HOWARD M. BARBER.
